MECHANISM FOR HOT STAMPING

Abraham Drucker, New York, and Patsy La Penna,
Brooklyn, N. Y.; said La Penna assignor to said
Drucker

Application June 5, 1940, Serial No. 338,882

2 Claims. (Cl. 101—110)

This invention relates to a selective numbering mechanism to stamp, imprint or emboss indicia upon articles such as leather, paper, and the like, by means of heated impressions.

An object of this invention is to provide a hollow spindle mounted in the forked arms of a bifurcated housing and having an electric heating element mounted in the hollow spindle for suitably heating the spindle while the housing is moved up and down for operating purposes.

Another object of this invention is to provide a plurality of number stamping disks rotatably mounted on the spindle, one side of each of said disks having an annularly shaped and peripherally recessed side extension serving to receive a spring to engage and hold the disk against accidental rotation.

Another object of this invention is to provide a crank pivotally mounted at one end of the housing and having an elongated spindle rotatably mounted at the free end thereof and the spindle having a number disk setting gear secured thereto and being jointly movable into engagement with the gear teeth on the stamping disks for selectively rotating said disks, and the crank being adapted to be turned radially away from the housing to permit movement of the setting gear into engagement with the gear teeth on one of the disks while out of contact with the heated housing.

Another object of this invention is to provide sight means positioned exteriorly of the number stamping disks and substantially in a horizontal plane above the disks, to provide a quick numbering index in front of the operator and so that the setting up and resetting of the indicia to be stamped can be accomplished in the least possible time.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a side elevation of a selective numbering mechanism which embodies the invention.

Figure 2 is an end view of the numbering mechanism, partly broken away.

Figure 3 is a plan view of one of the number stamping disks, in integral relation with a gear.

Figure 4 is a top plan view of the numbering mechanism.

Figure 5 is a cross-sectional view of the numbering mechanism, the section being taken as on line 5—5 in Figure 2, the heating unit being removed.

In the illustrated embodiment of the invention the numeral 10 indicates a selective numbering mechanism comprising a bifurcated housing 11 having a cylindrical upper extension 12. The fingers 13 of the bifurcated housing 11 have apertures 14. A hollow spindle 15 has been mounted in the apertures 14. A plurality of annular number stamping disks 16 have been rotatably mounted on the spindle 15. Each disk has an integral annular side extension 17. The peripheral surface of each side extension 17 has been formed into gear teeth 18.

Each disk 16 has a plurality of marginal slots 19 forming radially extending studs 20, each of which has been engraved to represent a digit. The gear teeth 18 have been positioned in alignment with the studs 20.

Elongated wire springs 21 have been secured to the rear of the housing 11 by being clamped by a bar 22 to the housing. The springs 21 depend vertically from the bar 22 and are aligned with the side extensions 17. The springs 21 have angularly shaped lower extensions 23 facing the side extensions 17 and are in axial alignment with the side extensions 23.

A crank 24 has been pivotally mounted on a pin 25 positioned in spaced relation above the spindle 15. An elongated spindle 26 has been rotatably mounted at the free end 27 of the crank 24 and has a number disk setting gear 28 secured at one end thereof adjacent the disks. A handle 29 has been secured to the outer end of the spindle 26. The operator may, by using the crank 24, slide the spindle 26 so as to bring the gear 28 into mesh with the teeth on the side extensions of any selected disk.

Normally, the angular extension 23 of a spring 21 is seated between two teeth of a disk 16 and holds the disk locked against rotation. It will thus be noted that when the gear 28 is rotated, the disk registering with the gear 28 will be rotated until the operator brings one of the slots 19 in said disk into alignment with the extension 23, when the spring 21 will move between two teeth and lock the disk against rotation.

For the purpose of this invention, which is to selectively rotate any desired stamping disk 16 so that a desired numeral will face downwardly for impressing purposes, we have duplicated the

digits appearing in engraved form on the outer periphery of the studs 20, on the bottom walls 29 of the slots 19. We have positioned the duplicate digits in spaced angular relation, approximately ninety degrees apart. Two sets of numerals from zero to 9, inclusive, are engraved on each disk. The operator may thus tell at a glance, by noting a numeral appearing below a sight bar 32, which digit will be impressed on the leather or paper article lying on the platen of a press in which the selective numbering mechanism 10 may be mounted for reciprocatory operating movements. Each disk has a stud 39 undercut so that a blank space may be had between numbers. The numbers zero to nine, inclusive, are engraved in the normally exposed surfaces of the studs, as shown by dot-and-dash lines in Figure 3, that is, the stamping numerals project out from the disks 16.

Mounted inside the hollow spindle 15 is an electric resistance heating unit 33 from which extend electric wires 34 which may be suitably connected to a source of electric current (not shown). An electric current passing through a high resistance wire causes the heating unit 33 to get hot and to heat the spindle 15 and the number stamping elements.

A set of numbered disks 16 have been mounted adjacent the right hand finger 13 and a set of numbered disks 16 have been mounted adjacent the left hand finger 13. Intermediate the said sets of disks has been mounted an elongated annular member 35 preferably of hexagonal cross-section. On one or more of the hexagonal faces may be formed indicia indicating the name of a concern, etc. It is thus possible to selectively adjust the various disks 16 and the central hexagonal member 35 to provide indicia which reads successively,

JOHN DOE
22 2032
N. Y.

consisting of a set of numerals, a name plate and another set of numerals. There is thus provided a set of numerals on each side of the name plate. The indicia shown is merely illustrative.

As shown in the drawings it will be noted that the sight bar 32 extends all the way across the housing 11 and is positioned parallel with the spindle 15. The lower face of the sight bar is in alignment with the two sets of numerals on opposite sides of the name plate member 35 and serves to indicate at a glance whether all the said numerals are properly set.

The hexagonal shape of the intermediate member 35 provides different peripheral spacing from the spacing of the studs 20 of the number disks 16. As shown in Figure 5, it will be seen that the uncut hexagonal faces are a bar to the axial movement of the setting gear 28 from one set of number disks to another set of number disks. The selective mechanism comprises at least three sets of type wheels or stamping devices each of which is resiliently held by a spring 21, and a setting member carried on a slidable shaft or spindle 26.

The selective numbering mechanism 10 thus described may have the cylindrical extension 12 secured in an aperture in the reciprocating plunger of a stamping press (not shown). The stamping press has a platen and may be actuated by a foot lever for causing reciprocatory movements of the plunger and the attached numbering mechanism to and from the platen.

It is to be noted that the mechanism herein described makes it possible to actuate any one of the stamping disks irrespective of the fact that the disks have been made so hot as to be 5 untoouchable by the hand of the operator. The setting gear 28 and the spindle 26 and handle 29 being removed to a position away from the periphery of the stamping disks and being thereby substantially fully exposed to the cooling air, 10 makes it possible for the operator to grasp the cool handle without feeling any undue effects of heat generated by the heating unit 33. It is also to be noted that the handle is made of a heat resisting material such as Bakelite or fiber.

15 We claim:

1. In a mechanism for hot stamping, the combination with a housing, a hollow spindle carried by said housing, said mechanism comprising at least two sets of toothed number stamping disks 20 and a non-toothed annular intermediate name plate stamping member rotatably mounted on said spindle, each of said stamping disks having a sideways extension comprising gear teeth in alignment with said number members, springs 25 intermediate said number disks, each of said springs being fixed to said housing and being in engagement with said gear teeth in said sideways extensions for individually locking said disks to said housing, a crank pivotally mounted on said 30 housing, an elongated spindle rotatably mounted at the free end of said crank and having a disk setting gear secured thereto, said spindle and said setting gear being movable into engagement with said gear teeth, whereby said number stamping 35 disks may be selectively engaged by said setting gear to cause rotation thereof by rotating said setting gear, said pivotally mounted setting gear being movable generally radially into a position clear of said name plate member to permit axial 40 movement of said spindle for bringing said setting gear past said name plate member and then movement generally radially into engagement with the teeth of said disks on the opposite side of said non-toothed name plate member, all of 45 said stamping devices being individually resiliently held during said movements.

2. In a mechanism for hot stamping, the combination with a housing having a spindle and two sets of toothed number stamping disks and 50 a non-toothed annular intermediate name plate member rotatably mounted on said spindle, each of said disks having coaxially disposed gear teeth means at one side thereof, springs in engagement with said gear teeth means holding each 55 of said stamping disks in operative position, an arm pivoted to said head and having a spindle slidably and rotatably mounted at its free end, said spindle having a setting gear secured at one end thereof, said arm being adapted to be 60 swung away from said head and thereby moving said setting gear generally radially outwardly to a position clear of said name plate member to permit axial movement of said spindle for bringing said setting gear past said name plate member and then movement generally radially and 65 inwardly into engagement with the gear teeth means of said disks on the opposite side of said name plate member, each of said disks having one set of numerals facing downwardly for impressing and having another set of numerals facing upwardly for indicating to the operator the character of said downwardly facing numerals.
